CHAIRSIDE TABLE

Joseph E. Adkinson, York, Pa., assignor to Weiman Co., Inc., Rockford, Ill., a corporation of New York

Filed May 28, 1962, Ser. No. 70,332

Term of patent 14 years

(Cl. D33—14)

FIG. 1 is a perspective view of a chairside table showing my new design,

FIG. 2 is a side view of the table, the opposite side which is not shown being identical, and

FIG. 3 is an end view of the table, the opposite end which is not shown being identical.

I claim:

The ornamental design for a chairside table, substantially as shown and described.
